UNITED STATES PATENT OFFICE

105,212

DESIGN FOR A BREAD RACK

Paul C. Fisher, Cedar Rapids, Iowa

Application May 14, 1937, Serial No. 69,350

Term of patent 7 years

To all whom it may concern:

Be it known that I, Paul C. Fisher, a citizen of the United States, residing at Cedar Rapids, in the county of Linn and State of Iowa, have invented a new, original, and ornamental Design for a Bread Rack, of which the following is a specification, reference being had to the accompanying drawing, forming a part thereof.

Figure 1 is a front view in perspective of a bread rack showing my new design, and

Figure 2 is a rear view in perspective thereof.

I claim:

The ornamental design for a bread rack as shown.

PAUL C. FISHER.
